UNITED STATES PATENT OFFICE.

CHARLES BROSSMANN, JR., OF INDIANAPOLIS, INDIANA.

FILTERING DEVICE.

No. 865,993.

Specification of Letters Patent.

Patented Sept. 17, 1907.

Application filed July 27, 1904. Serial No. 218,317.

To all whom it may concern:

Be it known that I, CHARLES BROSSMANN, Jr., a citizen of the United States, residing at Indianapolis, in the county of Marion and State of Indiana, have invented a certain new and useful Improvement in Filtering Devices, of which the following is a specification.

My invention relates to filtering devices, and has for its object to provide a new and improved device of this description.

10 My invention is illustrated in the accompanying drawing, wherein,

Figure 1 is a vertical sectional view through a filtering device embodying my invention, taken on line 1—1, Fig. 2; Fig. 2 is a sectional view taken on line 15 2—2, Fig. 1; Fig. 3 is a front view of one of the tiles; Fig. 4 is a sectional view taken on line 4—4, Fig. 3; Fig. 5 is a similar sectional view showing a modified construction; Fig. 6 is a view similar to Fig. 3 showing a further modification.

20 Like letters refer to like parts through the several figures.

One of the objects of my invention is to provide a filtering device which shall be cheap and efficient and durable, and which shall secure a substantially uniform operation of the entire filtering material.

As shown in the drawings, a reservoir, or other water holding device, may be used, and is provided with a bottom, A, of concrete, asphalt, or other material impervious to water. Upon the bottom A is a series of 30 tiles, B, which preferably cover the entire bottom. These tiles may be of various shapes. As shown in Figs. 1 and 2 the tiles are open at the bottom, and have simply two sides, one of which is inclined. These tiles are placed with the open side down, and the faces of 35 the two adjacent tiles meet at an angle to each other, as shown in Fig. 1, so that there is a space between the two tiles, and this space is filled with filtering material. The tiles are provided with openings through which the water or other material passes. These openings may be arranged in various ways. As shown in Fig. 4, these tiles have two faces, B¹ and B², which are at an angle to each other. An opening or inlet, B³, is located in the face B², and this opening is so situated that the water or other material which strikes the face 40 B¹ of the adjacent tile passes therewith so as to pass through the opening B³. It is, of course, evident that these openings may be arranged in other ways, and that the faces B¹ may also be provided with openings, if desired. As shown in Fig. 5, the tile is provided 45 with three sides, and as shown in Fig. 6, each tile is provided with two openings, B³. The water that passes into these openings is conducted along the bottom A and passes into the drain, or collecting device, C, and is then carried to the point desired. On the top of the 50 tiles B I provide a suitable filtering material. This filtering material may be formed in suitable layers,

and may be arranged in any suitable manner. The first layer is preferably made of coarse stone, and upon this coarse stone may be placed layers of finer stone, gravel or sand, the number of layers, the thickness 60 thereof, and the character of the material depending upon the conditions presented. It will be seen that this construction provides a bottom made up of a series of projections with spaces between them filled with filtering material, the whole mounted upon a sub-base 65 impervious to water. This construction provides a great saving in stone because of the shape of the tile, and particularly because of the inclined faces thereof. This construction also insures a direct flow toward all 70 parts of the bottom, and thus secures an even working of the filtering material; and a substantially even deposit upon the upper face thereof, and, consequently, the greatest efficiency is secured from the material.

In the operation of the device, the water—when the device is used for filtering water—passes down through the filtering material over all parts of the bottom, and strikes the tile and then passes through the inlets therein. Since the tiles are open at the ends, the water then has a free passage beneath the tiles and on top of the bottom, A, and finds its way to the collecting device, C.

I have described in detail a particular construction embodying my invention, but it is, of course, evident that the parts may be varied in many particulars, and I, therefore, do not limit myself to the construction shown.

It will be noted that the tiles are open at the ends, and when in position that they form a support for the filtering material made up of a series of ridges with spaces between them, into which the filtering material 90 is received. Each tile is provided with an inclined face, inclined with relation to the bottom or sub-base upon which the tiles are carried, and the inclined face abuts against the face of the adjacent tile. An inlet is provided in this face of the adjacent tile, at the bottom as it were of this inclined face, so that the liquid flowing down the inclined face enters the inlet and then passes along the passageway formed by the hollow tiles until it eventually reaches the collecting device, C. 95 It is, of course, evident that the inclined faces of the tiles may be provided with inlets, as shown, for example, in Fig. 5.

I claim:

1. A filtering device comprising a quantity of filtering material provided with a supporting base made up of a 105 series of substantially parallel projections with spaces between them into which the filtering material is received.

2. A filtering device comprising a receptacle having a bottom, a series of tiles upon said bottom provided with upwardly projecting parts separated by spaces and having 110 inlets associated therewith through which the liquid may pass, filtering material covering said projections and extending down into the spaces between the projections of the tiles.

3. A filtering device comprising a bottom part, a series of tiles resting thereon, each provided with an inclined upper face, and a quantity of filtering material above said tile, through which the liquid acted upon passes.
- 5 4. A filtering device comprising a bottom, a layer of filtering material located above said bottom, a series of upwardly projecting ridges along the bottom each having associated therewith an outlet for the water whereby a direct flow of the water toward all parts of the bottom is secured.
- 10 5. A tile for filtering devices made of a single piece and comprising two faces which meet at an angle, both of said faces extending to the base of the tile, one of said faces being inclined with relation to the support upon which the tile is carried when said tile is in its operative position.
- 15 6. A tile for filtering devices comprising an integral structure with two faces which meet at an angle, one of said faces being the upper face and inclined with relation to the support upon which the tile is carried when said tile is in its operative position, the walls of said tile being thinner than the length of either face, so that a space is formed between them.
- 20 7. A tile for filtering devices comprising two faces which meet at an angle, one of said faces being the upper face and inclined with relation to the support upon which the tile is carried when said tile is in its operative position, the walls of said tile being thinner than the length of either face, so that a space is formed between them, and an inlet in one of said faces communicating with said space.
- 25 8. A tile for filtering devices consisting of two sides or walls at an angle to each other, both walls projecting toward the support upon which the tile is carried and of different lengths, the space between the edges of said walls being open.
- 30 9. A tile for filtering devices having two faces at an angle to each other, one face being shorter than the other and being perpendicular to the base of the tile, the other face being inclined with relation to said base.
- 35 10. A tile for filtering devices triangular in cross sections and having an inclined upper face which forms an acute angle with the base thereof and a second face which supports said inclined face and an opening in one of said faces.
11. A filtering device comprising a sub-base, a series of tiles thereon, each having an inclined upper face, an inlet associated with each tile, filtering material associated with said tiles, and resting upon said inclined faces so as to have an indented surface.
12. A filtering device comprising a sub-base, a series of hollow tiles mounted thereon, each tile provided with an inclined face which abuts against the adjoining tile, and an inlet in the adjoining tile so that the liquid passing along the inclined face of one tile can enter the interior of the adjacent tile, and a quantity of filtering material above said tiles.
13. A filtering device comprising a sub-base, a series of hollow tiles thereon, each open at the ends so that a series of passageways are provided, a collecting device with which said passageways communicate, the upper face of each tile being inclined with relation to the sub-base, and a quantity of filtering material above said tiles.
14. A filtering device comprising a quantity of filtering material, a support upon which said material rests formed into a series of ridges with indentations between them, the filtering material filling these indentations, said support provided with outlet openings.
15. A tile for filtering devices having two faces at an angle to each other, one face being shorter than the other and being perpendicular to the base of the tile, the other face being inclined with relation to said base, said short face provided with an opening communicating with the interior of the tile.
16. A filtering device comprising a quantity of filtering material, a supporting base therefor having an uneven surface, a portion of the base at intervals projecting up into the filtering material and outlet openings in said supporting base.
